UNITED STATES PATENT OFFICE

ROBERT E. WOOLMAN, OF ST. JOSEPH, MISSOURI.

SHOE-TIP CLAMP.

SPECIFICATION forming part of Letters Patent No. 716,608, dated December 23, 1902.

Application filed January 20, 1902. Serial No. 90,454. (No model.)

To all whom it may concern:

Be it known that I, ROBERT E. WOOLMAN, a citizen of the United States, residing at St. Joseph, in the county of Buchanan, State of Missouri, have invented certain new and useful Improvements in Shoe-Tip Clamps; and I do hereby declare the following to be a full, clear, and exact description of the invention, such as will enable others skilled in the art to 5
10 which it appertains to make and use the same.

This invention relates to holding devices or clamps for shoe tips, linings, tops, stays, and other parts of shoes; and it has for its object to provide a simple and efficient device of 15 this nature in which a number of duplicate parts may be securely held, thus doing away with tying with twine, as is usual, which method is slow and is further objectionable in that the twine cannot be used a second time. 20 With the present invention, the specific structure of which is modified to accommodate the different parts, the parts are held securely, but in such manner that they may be easily and quickly inserted and removed, 25 the clamp or holder being used repeatedly until entirely worn out.

In the drawings forming a portion of this specification, and in which like numerals of reference indicate similar parts in the several 30 views, Figure 1 is a perspective view showing the clamp formed to hold tips, the clamping-arms thereof being shown in active positions. Fig. 2 is a longitudinal central section of the clamp or holder with a series of tips held 35 therein. Fig. 3 is a perspective view of one of the clamping-arms. Fig. 4 is a top plan view showing a modification. Fig. 5 is a perspective view of the modified form of clamping-arm. Fig. 6 is a section on line 6 of 40 Fig. 1.

Referring now to the drawings, it will be seen that the present clamp or holder comprises a two-part base, including the two similar members 5 and 6, each of which has a broadened end portion 7 and 8, respectively, 45 which is slit longitudinally, so that there are formed the two tongues 9 and 10, the members being of elastic material, so that the tongues are spring-tongues. The metal at 50 each side of each of the spring-tongues is rolled to form the two transverse alining tubular bearings 11 and 12 on each of the members

5 and 6, the rolling of the metal in the formation of these tubular bearings resulting also in permitting the spring-tongues to project 55 beyond the bearings, as illustrated.

In connection with each of the members 5 and 6 there is employed a clamping-arm 13, which in the present instance is shown as formed of a single wire and is of quadrilateral form, with two of the sides 15 and 16 parallel and lying transversely of the member. The side 15 includes both end portions of the wire, and these end portions are bent to aline and extend toward each other and 60 are engaged in the tubular bearings, as shown in Fig. 1. The extremities of the wire are taken inwardly beyond the inner ends of their respective bearings, and one end is then bent laterally at right angles, so that when 65 the arms are in the positions shown in Fig. 1 of the drawings the laterally-bent portions or fingers 17 and 18 will press against and displace the tongue of the corresponding member 5 and 6 to place the tongue under tension, 70 the tension of the tongue acting to hold the clamping-arms against the tips, as shown in Fig. 2.

The two members 5 and 6 are slidably connected, so that the relative positions of the 80 clamping-arms may be adjusted to compensate for different widths of articles to be held. To hold the members 5 and 6 slidably, they are disposed one against the other and have 85 ears 20 formed at their outer edges, the ears of each member being bent to lie upon the outer face of the other member.

To limit the outward movement of the members 5 and 6 comparatively, the member 5 has a struck-up portion or boss 22, adjacent to its 90 narrowed end, and this boss engages a groove 23 in the member 6, formed by striking up the central portion of member 6 on a central line. When the members 5 and 6 are drawn outwardly to their limit, the free end of the boss 95 strikes the end wall of the groove and limits the movement of the members.

With this construction it will be seen that the holder or clamp comprises only four parts and that it is cheap and easy of manufacture 100 and may be made of inexpensive material. Further, it will be understood that in practice the clamping-arm may be of any desired specific shape to facilitate holding special

forms and that other modifications may be made and any suitable materials and proportions may be used for the various parts without departing from the spirit of the invention.

5 In Figs. 4 and 5 of the drawings there is shown a modification of the invention, where-
in one member 30 of the base has the trans-
verse alining tubular bearings 31 and 32, cor-
responding to those of the members 5 and 6,
10 and an intervening spring - tongue 33, the
members 30 and 34 being connected adjust-
ably in the same manner as shown in the con-
struction above described. The second mem-
ber 34, however, while having the transverse
15 spaced bearings 35 and 36, has no intervening
tongue, the bearings projecting beyond the
end of the member and being separated by an
interspace, as shown. In connection with the
member 34 of the base is employed a clamp-
20 ing-arm 37, formed of a single wire including
spaced members 38 and 39 and a connecting
portion, as shown, the free ends of the mem-
bers being bent toward each other at right an-
gles and continued until they touch and be-
25 ing then bent in the same direction and at
right angles to the plane of the members 38
and 39 and their connecting portion. The
rearwardly-bent ends 40 and 41 of the mem-
bers when the arm is at a right angle to the
30 member 34 lie against the under side of the
member 34 and act as a stop to prevent far-
ther outward movement of the arm, while
permitting movement thereof toward the base
into clamping position. This arm is specially
35 designed for use in connection with certain
portions of the shoe. In connection with a
second member of the base there is employed
a clamping-arm, as shown in Fig. 4 of the
drawings, wherein the extremities of the wire

of which the arm is made are bent at right 40
angles, but in the plane of the arm, so that
they may engage the spring-tongue 33 and
place it under tension in the same manner in
which the spring-tongues 9 and 10 are en-
gaged by the portions 17 and 18 of Fig. 1, 45
the spring-tongue 33 holding the clamping-
arm yieldably in clamping position.

What is claimed is—

1. A device of the class described comprising a base including adjustably-connected 50 members, a clamping-arm mounted upon each member for movement toward and away therefrom, into and out of operative position, and means for holding the clamping-arms yieldably in active positions. 55

2. A device of the class described comprising a base including adjustably-connected members, and clamping-arms mounted upon the members and movable toward and away from each other into and out of clamping re- 60 lation to the base.

3. A device of the class described comprising a base including two members slidably connected and each having its outer end slotted to form a tongue, each member being bent 65 at each side of its tongue to form a tubular bearing, and an arm engaged with the bearings of each member and having a project-
ing portion disposed to engage the adjacent tongue and place it under tension when the 70 arm is moved to clamping position.

In testimony whereof I affix my signature in presence of two witnesses.

ROBERT E. WOOLMAN.
